UNITED STATES PATENT OFFICE.

FRANK HARDIE JEANNIN, OF ARCADIA, FLORIDA.

ELECTRICAL TRANSFORMER.

SPECIFICATION forming part of Letters Patent No. 579,895, dated March 23, 1897.

Application filed April 1, 1895. Renewed February 15, 1897. Serial No. 623,580. (No model.)

To all whom it may concern:

Be it known that I, FRANK HARDIE JEANNIN, of the city of Arcadia, De Soto county, State of Florida, have invented certain new and useful Improvements in Transformers, of which the following is a full, clear, and exact description, reference being had to the accompanying drawings, forming a part hereof.

My invention relates to an improved transformer; and it consists in the novel construction, combination, and arrangement of parts hereinafter described and claimed.

In the drawings, Figure 1 is a side elevation of my improved transformer, the same being located in a suitable casing, a portion of said casing being broken away. Fig. 2 is a vertical sectional view of my improved transformer after the same has been properly wound and before the ends are lapped over and properly fastened. Fig. 3 is an enlarged horizontal sectional view taken approximately on the indicated line 3 3 of Fig. 2. Fig. 4 is a vertical sectional view of the upper portion of one of the improved transformers after the same has been properly wound and finished.

Referring by numerals to the accompanying drawings, 1 indicates a suitable casing that may be of any size and form desired, 30 said casing being constructed with perforated ears 2, whereby it is fastened at any suitable point. Said casing 1 is provided with the top plate 3, that is fastened to said casing by screws, bolts, or in any suitable manner.

4 indicates a bundle of soft-iron wires cut in uniform lengths, and said bundle of soft-iron wires comprises the core of my improved transformer.

5 indicates the secondary coil, which is 40 preferably of copper wire and the ends 6 of which are so arranged as that connections can easily be made thereto.

7 indicates a series of soft-iron wires that are cut at different lengths, and 8 the primary coil, which is preferably of copper wire, its 45 ends being so arranged as that connections can be easily made thereto. Suitable insulating material is indicated by heavy black lines in the drawings.

50 In winding or constructing a transformer of my improved form a bundle of soft-iron

wires, such as 4, of the desired length are covered with suitable insulation. The secondary coil, preferably of copper wire properly insulated, is now wound directly upon 55 this bundle of soft-iron wires, and the ends 6 thereof are left projecting some distance from the outside ends of the bundle of iron wires which constitute the core of the transformer. A layer of soft-iron wires such as 60 7, are now located directly upon the secondary coil, said layer of wires lying parallel with the core composed of the iron wires 4 and the ends of said wires 7 projecting a slight distance beyond the ends of said core. 65 Said layer of iron wires are now properly insulated and a single layer of the primary coil 8 is now wound over this first layer of iron wires 7, said first layer extending the entire length of the core 4. A second layer of iron 70 wires 7 are now laid upon the first layer of the primary coil, said second layer of iron wires 7 being properly insulated. A second layer of the primary coil is now wound upon this second layer of iron wires 7, and this 75 method of winding or alternating the longitudinally-extending iron wires 7 with the layers of the primary coil is continued until the transformer is of the proper size.

It is essential that the ends of all the wires 80 7 protrude some distance from the ends of the core 4. When the transformer is of the proper size, a part of these ends are lapped over toward the center of the core 4, as indicated by A in Fig. 4. The remaining ends 85 or the ends of the outside layers of the iron wires are lapped over the outside of the last coil of the primary wire to meet approximately at the center of the transformer, as indicated by B, Fig. 4. The transformer thus completed 90 is located in a casing, such as 1, and the ends of the primary and secondary coils brought through suitable apertures in said casing and the proper connections made thereto.

A transformer of the construction herein- 95 before described is very compact and is very easily and expeditiously constructed.

The longitudinally-extending wires 7, as may be plainly seen, constitute a portion of the core, and by so locating them between 100 the copper-wire coils a transformer is constructed that possesses superior advantages

in point of simplicity, durability, and general efficiency.

What I claim is—

The improved converter, having a core made up of soft-iron wires $\frac{1}{4}$ all of one length, a separate series of soft-iron wires of various lengths, and a magnetic circuit formed by the varied lengths of soft-iron wires placed between the layers of copper wire composing the primary and secondary coils, and the projecting ends A of the wires between the layers next adjacent the core being bent inward

across the end of said core, and the others B being bent outward and lapped over each other, and an exterior casing for holding in position such lapped-over portions, substantially as herein specified.

In testimony whereof I affix my signature in presence of two witnesses.

FRANK HARDIE JEANNIN.
